FOUNTAIN PEN

William H. Huenergardt, Chicago, Ill., assignor
to Milton Reynolds, Chicago, Ill.

Application December 13, 1945, Serial No. 634,742

5 Claims. (Cl. 120—43)

1

The present invention relates generally to fountain pens. More particularly the invention relates to that type of fountain pen which is known as a ball pointed pen and comprises an elongated tubular body which is adapted in connection with a writing operation to be held by the user in an upright position, has in its interior a column or mass of quick drying paste variety ink, embodies at its lower end a tip having a depending downwardly tapered annular wall which forms an ink chamber in communication with the interior of the body and surrounds a freely rotatable ball for applying ink over the writing surface by a rolling action, and has at its upper end a closure member which is removably secured in place by way of a reduced externally threaded stem and serves, when removed, to expose the upper end of the body in order that the latter may be recharged with ink.

As evidenced by United States patent application Serial No. 619,329, filed by me on September 29, 1945, it has heretofore been proposed to employ in a fountain pen of the aforementioned type a cylindrical member which fits slidably in the tubular body, theoretically rests on the column of ink and follows the ink downwards as the latter is consumed, is intended to prevent air in the upper end of the body from working itself into the ink and forming bubbles which, upon entry into the ink chamber in the tip, would preclude proper writing by the ball, and, in addition, is intended to preclude displacement of the mass of ink in the direction of the upper end of the body when the pen is placed or laid on its side and thus prevents air from seeping into the ink chamber in the tip between the ball and its seat and causing an air-lock which would preclude writing on the part of the ball. Heretofore the cylindrical member has been formed of solid metal. In practice it has been found that when the cylindrical member is formed of solid metal that has a higher specific gravity than the ink it does not serve or fulfill its intended purpose because it gradually moves by gravity downwards through the ink and when brought to rest near the tip blocks further flow of ink into the ink chamber.

The primary object of the instant invention is to provide a ball pointed fountain pen which is an improvement upon, and eliminates the defects of, previously designed pens of the same general character, including that of the aforementioned patent application, and is characterized by the fact that the cylindrical member, instead of being formed of solid metal, is hollow to the end that

2

it has less specific gravity than the ink and hence floats on the column or mass of ink and effectively and efficiently fulfills its intended purpose.

Another object of the invention is to provide a ball pointed fountain pen of the type under consideration in which the tubular body has in the upper end thereof and directly beneath the lower end of the internal screw thread for the stem of the removable closure member a wad which is formed of compressible fibrous material, such, for example, as felt and has a twofold purpose in that it serves to prevent dust and other foreign material from entering the body interior when the closure member is removed from its normal operative position, and, in addition, serves to prevent the ink in the body from creeping upwards into the internal screw thread by capillary action and forming a film which coats the external screw thread on the stem of the closure member and is extruded onto the outer surfaces of the body and closure member when the member, after removal, is again applied to the body. A further object of the invention is to provide a ball pointed fountain pen which is simple in design and construction and is highly efficient in operation.

Other objects of the invention and the various advantages and characteristics of the present fountain pen will be apparent from a consideration of the following detailed description.

The invention consists in the several novel features which are hereinafter set forth and are more particularly defined by claims at the conclusion hereof.

35 In the drawing which accompanies and forms a part of this specification or disclosure and in which like numerals of reference denote corresponding parts throughout the several views:

Figure 1 is a side view of a fountain pen embodying the invention;

Figure 2 is a longitudinal section of the pen, showing in detail the manner in which the cylindrical member floats on the column or mass of ink in the body of the pen;

Figure 3 is an enlarged longitudinal section of the cylindrical member, illustrating in detail the construction and design of such member; and

Figure 4 is an enlarged longitudinal section of the lower or tip end of the pen.

The fountain pen which is shown in the drawing constitutes the preferred form or embodiment of the invention and comprises as its principal parts or components an elongated tubular body 6, a tip 7, a ball 8, a float type cylindrical member 9, and a wad 10.

The body 6 is adapted in connection with a writing operation to be held by the user of the pen in an upright position and is preferably formed of any suitable material, such, for example, as aluminum. As shown in Figure 2 the 5 interior of the body is shaped to define a large sized cylindrical compartment 11, an ink duct 12 and a socket 13. The compartment 11 is formed in the central and upper end portions of the body and is adapted to be filled with a column or mass 14 of paste variety ink. The latter is preferably of the quick drying type and is introduced into the compartment 11 through the upper end of the body 6. The upper end of the compartment extends through the upper end face of the body and is normally closed by a removable, elongated closure member 15 which when in its operative position forms a part of the body. As shown in Figure 3, the closure member 15 embodies at its lower end a reduced externally threaded stem 16 which is shaped to fit within the upper end of the body 6 and coacts with an internal screw thread 17 on the upper end of the body. When the closure member is in place it serves to prevent outflow of ink through the upper end of the body. When it is desired to expose the upper end of the body in order that the latter may be recharged with ink the closure member 15 is removed by unscrewing it from the upper end of the pen body 6. The closure member is preferably upwardly tapered. As shown in the drawing, the diameter of the lower end of the closure member is the same as the external diameter of the upper end of the body. The duct 12 and the socket 13 are formed in the lower end portion of the body. The duct is cylindrical and communicates with, and leads downwards from, the lower end of the compartment 11. It is of materially less diameter than the compartment and serves as hereinafter described to conduct ink from the compartment to the tip 7. The socket 13 communicates with, and leads downwards from, the lower end of the duct 12 and extends through the lower end face of the body.

The tip 7 is located at the lower end of the body and is preferably formed of steel or like hard durable metal. It is circular in cross section and embodies at its upper end an upwardly tapered stem 18 which is shaped conformably to, and is driven into connected relation with, the socket 13 in the lower end of the pen body 6. The lower end of the tip is downwardly tapered and embodies an integral annular wall 19, which defines an ink chamber 20. The latter is in communication with, and receives ink from, the duct 12 by way of a duct 21 which, as best shown in Figure 5, is formed in the central portion of the tip 7, extends downwards from the lower end of the duct 21 and opens onto the central upper portion of the ink chamber 20. The lower end of the annular wall 19 of the tip 7 defines a circular seat 22. When the pen is in use ink flows from the compartment 11 downwards into the ink chamber 20 via the ducts 12 and 21. The lower end of the body 6 is downwardly tapered and has substantially the same external contour as the closure member 15.

The ball 8 is truly spherical and is preferably formed of steel. It is disposed for the most part in the ink chamber 20, as shown in Figure 5, and is arranged so that the portion thereof beneath its center rests slidably against the circular seat 22 at the lower end of the annular downwardly tapered wall 19 of the tip 7. The seat 22 serves to retain the ball rotatably in place with

the upper portion thereof in sliding engagement with the lower end of the duct 21. In connection with a writing operation the ball 8 rolls over the writing surface and applies ink to the surface from the ink chamber 20. The ink by reason of the fact that it is in paste form has pronounced lubricating properties with the result that the ball is freely rotatable.

The cylindrical member 9 is mounted for free sliding movement in the upper end of the cylindrical compartment 11 and floats on the column or mass of ink in the body. It is hollow, as shown in Figure 3, and has a twofold purpose in that it prevents air in the upper end of the body from working itself into the ink and forming bubbles, and in addition precludes displacement of the mass of ink in the direction of the closure member 15 when the pen is placed or laid on its side. Preferably the member 9 is formed of light weight metal, such, for example, as aluminum. As shown in Figure 3 the member 9 comprises an inverted cup-shaped part 23 and a disc 24. The cup shaped part 23 consists of a circular top wall 25 and a depending cylindrical skirt 26. The skirt has its upper end connected to the marginal portion of the circular top wall 25 and embodies at its lower end an internal annular groove 27. The external diameter of the skirt of the float type cylindrical member 9 is slightly less than the diameter of the ink compartment 11 in the upper and central portions of the body 6 in order that the cylindrical member 9 is free to slide lengthwise of the compartment. The upper end of the groove 27 in the lower end of the cylindrical skirt 26 is defined by an annular downwardly facing shoulder 28. The disc 24 serves as a closure for the lower end of the inverted cup-shaped part 23 and fits snugly within the groove 27. As shown in Figure 3 the marginal portion of the disc abuts against the annular downwardly facing shoulder 28. The lower end of the skirt 26 is crimped around and under the marginal portion of the disc 24 in order that the disc is fixedly secured or held in place. As a result of the fact that the cylindrical member 9 is hollow the member as a whole actually floats on the column or mass of ink in the cylindrical ink compartment 11 and does not in response to the action of gravity work its way down into the ink. It is contemplated that when the pen is originally charged with ink the compartment 11 will only be partially filled. After charge of the compartment to the desired extent the cylindrical member 9 is inserted into the upper end of the body and is then slid downwards until the bottom face thereof is in engagement with the column or mass of ink. Because of the adhesive tendency of the ink the float type cylindrical member 9 adheres to the upper end of the mass of ink and follows the ink downwards as the latter is consumed in connection with use or writing of the pen. When the cylindrical member 9 is in place it seals the column or mass of ink against contact with the air in the upper end of the tubular body 6 and hence no air is permitted to work itself in bubble form into the ink. As heretofore pointed out, the float type cylindrical member follows and adheres to the ink and prevents dislodgement of the ink in the direction of the closure member when the pen is laid or placed on its side or positioned with the tip at the top. By preventing or precluding displacement of the ink in the direction of the closure member when the pen is laid on its side there is no tendency for air to seep into the ink cham-

ber 20 in the tip and result in an air-lock which would preclude the flow of ink into the ink compartment and resultant failure of the ball in the tip to write. The height of thickness of the disc 24 is less than the height of the groove 21 and hence the metal at the lower end of the skirt that is crimped around and under the marginal portion of the disc defines with the lower face of the disc a shallow cavity 29. By reason of the fact that this cavity is present the ink works into the cavity when the cylindrical member is shifted into place and because of its adhesive properties effects such an adhesive bond with the cylindrical member that the latter is caused substantially positively to follow the ink downwards as it is consumed. The inner face of the crimped metal, due to crimping, is upwardly flared with the result that the margin of the cavity 29 is undercut and hence the paste variety ink at the top of the column interlocks with the cavity so as to cause the float type member and the ink column to be locked or connected together. The circular top wall 25 of the inverted cup shaped part 23 of the float type cylindrical member is provided with an upstanding centrally disposed handle 30 whereby the member 9 may be gripped in connection with its insertion into and removal from the body. Preferably the handle is in the form of an enlarged head 31 which is joined to the central portion of the circular top wall 25 by a reduced neck 32. Because of the shape of the component parts of the handle the handle may be gripped by a tweezers having the ends of the nibs thereof turned inwards.

The wad 10 is cylindrical or disc-like and fits snugly within the upper end of the tubular body 6 at a point directly beneath the lower end of the internal screw thread 17. It is formed of compressible fibrous material, such, for example, as felt, and serves not only to prevent dust from entering the body and contacting the ink when the removable closure member is removed from the body but also to prevent the ink in the body from creeping upwards by capillary action and forming a film on the screw thread 17. If a film of ink were formed on the screw thread 17 it would coat the externally threaded stem 16 on the lower end of the closure member 15 and result in ink being extruded onto the outer surfaces of the body and closure member when the member, after removal from the body, is again screwed onto the body. The diameter of the wad 10 is preferably greater than the internal diameter of the body in order that the wad when inserted into place is compressed. By reason of the fact that the wad is formed of fibrous material it does not prevent inflow of air into the body interior upon removal of the closure member 15. Actually the wad permits air in the upper end of the body to circulate past it into the space above the float type member 9.

The herein described ball pointed fountain pen is highly efficient in operation due to the fact that it includes the cylindrical float type member 9 and the wad 10.

The invention is not to be understood as restricted to the details set forth since these may be modified within the scope of the appended claims without departing from the spirit and scope of the invention.

Having thus described the invention what I claim as new and desire to secure by Letters Patent is:

1. In a fountain pen comprising a tubular body adapted in connection with a normal writing op-

eration to be held in an upstanding position, having the interior thereof cylindrical and adapted to hold a partial filling of paste variety ink, embodying at its upper end vent means, provided at its lower end with a freely rotatable spherical ball for applying the ink to a writing surface, a hollow, cylindrical float type follower of but slightly less diameter than the interior of the body, mounted in the body so that it is free to slide from one end thereof to the other, adapted in response to the action of gravity and the pressure of the superjacent air in the body to follow the ink downwards during normal writing of the pen, further adapted when the pen is placed on its side to prevent displacement of the ink in the direction of the normal upper end of the body, and consisting of an inverted cup-shaped part, and a disc-like part fitting within the lower end of the skirt of the cup-shaped part, said lower end of the skirt being crimped around the margin of the disc-like part so that it secures the latter in place and having the inner periphery thereof upwardly flared so that it together with the bottom face of said disc-like member defines a shallow concentric undercut cavity for receiving and interfitting with a portion of the upper end of the ink filling.

2. In a fountain pen comprising a tubular body adapted in connection with a normal writing operation to be held in an upstanding position, having the interior thereof cylindrical and adapted to hold a partial filling of paste variety ink, embodying at its upper end vent means, and provided at its lower end with a freely rotatable ball for applying the ink to a writing surface, a hollow, cylindrical follower of but slightly less diameter than the interior of the body, embodying a circular top wall and a depending skirt, mounted in the body so that it is free to slide from one end thereof to the other, adapted in response to the action of gravity and the pressure of the superjacent air in the body to follow the ink downwards during normal writing of the pen, and further adapted when the pen is placed on its side to prevent displacement of the ink in the direction of the normal upper end of the body.

3. In a fountain pen comprising a tubular body adapted in connection with a normal writing operation to be held in an upstanding position, having the interior thereof adapted to be partially charged with paste variety ink, embodying at its upper end vent means and also a removable closure member, and provided at its lower end with a freely rotatable ball for applying the ink to a writing surface, a wad of compressible fibrous material compressed laterally and held frictionally within the upper end of the tubular body at a point substantially directly beneath the removable closure member and above the ink and adapted to prevent the ink from working its way to the vent means while at the same time permitting air from said vent means to flow through it into the space above the ink.

4. In a fountain pen comprising a tubular body adapted in connection with a normal writing operation to be held in an upstanding position, having the interior thereof cylindrical and adapted to be partially charged with paste variety ink, embodying vent means at its upper end, and provided at its lower end with a freely rotatable ball for applying the ink to a writing surface, a hollow cylindrical follower of but slightly less diameter than the interior of the body mounted in the body so that it is free to slide from one end thereof to the other, arranged and adapted to

float on top of the mass of ink without appreciable penetration and also in response solely to the action of gravity and the pressure of the superjacent air in the body to follow the ink downwards during normal writing of the pen, and further adapted when the pen is placed on its side to prevent displacement of the ink in the direction of said upper end of the body, and a wad of compressible fibrous material compressed laterally and held frictionally within the upper end of the tubular body at a point above the follower but beneath the vent means and adapted to prevent the ink from working its way to said vent means by capillary action while at the same time permitting air from the vent means to flow through it into the space above the follower.

5. In a fountain pen comprising a tubular body adapted in connection with a normal writing operation to be held in an upstanding position, having the interior thereof cylindrical and adapted to be partially charged with paste variety ink, embodying vent means at its upper end, and provided at its lower end with a freely rotatable ball for applying ink to a writing surface, an oversized cylindrical wad of felt material fitting snugly within the upper end of the tubular body at a

10 5 point beneath the vent means and above the ink and adapted to prevent the ink from working its way to the vent means while at the same time permitting air from said vent means to flow through it into the space above the ink.
